PUSH BUTTON ELECTRICAL SWITCH

John Doggart, Macclesfield, England, assignor to V & E Friedland Limited, Macclesfield, Cheshire, England, a British company

Filed Sept. 9, 1968, Ser. No. 13,463

Claims priority, application Great Britain Mar. 26, 1968

Term of patent 14 years

Int. Cl. D13—03

U.S. Cl. D26—13

FIG. 1 is a front view of a push button electrical switch embodying my new design,

FIG. 2 is a view of one side of the push button electrical switch, from the right,

FIG. 3 is a rear view of the push button electrical switch,

FIG. 4 is a plan view of the push button electrical switch,

FIG. 5 is a section on the line 5—5 in FIG. 1 of the push button electrical switch, and

FIG. 6 is a perspective view from above and one side of the push button electrical switch.

I claim:

The ornamental design for a push button electrical switch, substantially as shown.
